United States Patent Office.

H. S. SHEPARDSON, OF SHELBURNE FALLS, MASSACHUSETTS.

Letters Patent No. 99,013, dated January 18, 1870.

IMPROVED LOCK

The Schedule referred to in these Letters Patent and making part of the same.

To all whom it may concern:

Be it known that I, H. S. SHEPARDSON, of Shelburne Falls, Franklin county, State of Massachusetts, have invented certain new and useful Improvements in Locks; and I do hereby declare that the following is a full and clear description thereof, reference being had to the accompanying drawings, and to the letters of reference marked thereon.

In the drawings—

Figure I is a side sectional view through a door, and my lock attached.

Figures II and III are cross sectional views through parts of the same, showing different positions of the interior works.

Figure IV is a partial sectional view in detail.

Figure V is a detail view accompanying Fig. I.

In construction, I form my lock of a case, F, containing the tumbler-holder H, which is operated by means of the flat key X.

An auxiliary cam, D, operates the main lock, and a connecting-piece, Y, connects the tumbler-holder in the case F on one side of the door, and the cam D, operating the main lock on the other side of the door. This piece Y is adjusted in length to fit the thickness of door.

The construction of the lock contained in the case F is as follows:

The tumbler-holder is turned by a flat key, which passes into the lock through a number of sliding tumblers, a a, the slots m of which are made through the middle; and although these slots m are of different lengths, the lower ends are all upon the same line when the key is in place, the lock being in the position shown in Fig. I.

The upper edge of the key is raised or depressed to suit the width of slot m, the sliding tumblers coming opposite to the relative parts when in place, and, when this is the case, the ends of the sliders are flush with the surface of the tumbler-holder on both sides, and the latter is free to be turned by the key.

When the key is out, however, the tumblers spring up, operated by coil-springs, hereafter described, and their outer ends pass through slots K K in the case F, immediately over the tumbler, so that the tumbler-holder cannot be turned until the tumblers be withdrawn.

The tumblers are here provided with projections f, to further prevent them from being illegitimately withdrawn; these projections f catching over the edge of the slots K, when the tumbler-holder is not in exactly the proper position for unlocking.

It is shown in fig. V that the tumblers are constructed with arms e projecting from their sides. These arms set into the upper parts of sockets d d in the tumbler-holder, and into these sockets are placed coil-springs, which tend always to throw up the tumblers. When the key is in place, these coil-springs are compressed with the descent of the tumbler, between the lower edge of the arm and the bottom of the socket.

The case F surrounding the tumbler-holder is provided with screw-threads, at p, and an outer case, G, screws over it.

Into this case or sleeve G, the screws E E, connecting the two parts of the lock on opposite sides of the door, are screwed, they passing through a washer, C, which also forms the bearing for the cam D.

Now, having described my invention,

What I claim as new, and desire to secure by Letters Patent, is—

In combination with the case G, the tumblers a a, &c., constructed with the slots m and springs d, arranged, as described, within the tumbler-holder H, and operating, in connection with the case F, as set forth.

H. S. SHEPARDSON.
